UNITED STATES PATENT OFFICE.

FREDERICK GRIMME, OF CHICAGO, ILLINOIS, ASSIGNOR OF ONE-HALF TO
ALEXANDER A. WHAMOND, OF CHICAGO, ILLINOIS.

LOOSE-LEAF-BINDER FRAME.

No. 796,322.

Specification of Letters Patent.

Patented Aug. 1, 1905.

Application filed August 24, 1903. Serial No. 170,636.

To all whom it may concern:

Be it known that I, FREDERICK GRIMME, a citizen of the United States, residing at Chicago, in the county of Cook and State of Illinois, have invented certain new and useful Improvements in Loose-Leaf-Binder Frames, of which the following is a specification.

This invention relates to loose-leaf-binder frames for holding ledger and other leaves, circulars, catalogues, &c.; and its object is to provide a frame of simple and inexpensive construction adapted to receive and hold the leaves securely and evenly and permit them to be easily inserted or removed.

Further objects of the invention are to provide a binder-frame with a round back and to cause the stub end of the leaves to spring up like a spring-back book and the leaves to lie flat when the book is opened.

In the accompanying drawings, illustrating one embodiment of the invention, Figure 1 shows the binder opened and with a number of leaves held therein. Fig. 2 shows the binder in position for inserting leaves. Fig. 3 is a top plan view of the binder. Fig. 4 is a sectional view on the line 4-4 of Fig. 3. Fig. 5 is an end view of the binder without the leaves. Figs. 6 and 7 are sectional views on the lines 6-6 and 7-7, respectively, of Fig. 3. Fig. 8 is a detail view of a portion of the spring-roller. Fig. 9 shows a device on the end of the tape by means of which the tape is fastened to the roller. Fig. 10 shows the means for supporting and securing one end of the roller. Fig. 11 is a plan view of a part of my improved leaf. Fig. 12 is an enlarged sectional view on the line 12-12 of Fig. 11. Fig. 13 is a detail perspective view showing another form of clamping-plate. Fig. 14 is an end view of a binder-frame, showing a different manner of securing the covers.

Like numerals of reference indicate corresponding parts in the several figures, and referring thereto 15 indicates the back of the frame, which is preferably provided with a covering 16, of leather or other suitable material. This back is made of resilient material, such as fiber board or spring-steel, and is formed in any suitable way into the shape of a round-back book. I prefer to form the back into a half-circle, as illustrated in Fig. 5; but the degree of curvature can be varied as desired. A spring-roller 17 is mounted in bearings within the back, these bearings be-

ing shown in the drawings to be formed in the upstanding ends 18 18' of a plate 19, fastened to the back. One of these ends 18' is provided with a slot 20 to receive the projecting end of the axle 21, and the axle is supported and held in place by the locking-plate 22, Fig. 10. One end 23 of the axle is screw-threaded to receive a key 24, Fig. 4, by means of which the spring 25 of the roller can be wound up; but instead of this screw-threaded connection of the key with the axle other constructions may be used, if preferred. I do not restrict myself to the use of any particular kind of spring-roller, as it will be apparent that different varieties may be used with satisfactory results and without modifying the invention. A pawl 26 is provided on the end 18 to engage a ratchet 27 on the roller and prevent the spring from unwinding, the engagement of the pawl with the ratchet being maintained by a spring-arm 28, fastened to the end 18 and bearing against a shoulder 29 on the pawl, Figs. 3, 5.

The leaves are adapted to be held on flexible tapes 30, of fabric, leather, or other suitable material, and each of these tapes travels over a guide at one edge of the back and has one end fastened at the other edge of the back and its other end fastened to the spring-roller. Any suitable number of these tapes may be employed, and I prefer to attach some of the tapes at one edge of the back and some to the other edge, so that they will travel in opposite directions from the spring-roller. At each edge of the back I provide rollers 31, mounted on clamping-plates 32, and the ends of the tapes are attached to some of these rollers, while the others form guides over which the tapes travel. The covers 33 are hinged to the back by pivot-pins 34, arranged in lugs 35 on the plates 32, and the hinge-plates 36 on the covers, Fig. 3, and the upper edge 32' of said plates 32 is inwardly directed or bent to engage and clamp the leaves, Figs. 6, 7. These clamping-plates may be formed of sheet metal pressed into shape, as shown in Fig. 13, with lugs 31' stamped up to form bearings for the rollers 31. Instead of hinging the covers in the manner shown in Fig. 3 I may secure pieces of cloth 33' between the back 15 and the clamping-plates 32 and secure the covers thereto in a manner familiar in the bookbinders' art. This construction is well adapted for small binder-frames for hold-

ing price-lists. The tapes may be attached to the spring-roller in a variety of ways, and I have shown a plate 37, Fig. 9, carried by the end of the tape and curved to fit the roller and provided with a headed projection 38, which is adapted to enter the transverse slot 39 in the hollow spring-roller, Fig. 8, and make locking engagement with the roller when turned into operative position.

I prefer to employ a leaf 40 which has its stub end reduced in thickness at 41 and scored at 42 and provided with T-slots 43 to receive the tapes, said sheet forming the subject-matter of my application, Serial No. 170,637, filed on August 24, 1903. To enable the sheets to be readily inserted in the back, I provide at each end of the frame a spreader 44, made in two parts and pivoted together at 45. These spreaders are pivoted at one end on the pins 34 at one side of the frame and are provided with sockets 46 at their other ends to engage the pins 34 at the other side of the frame, as indicated in broken lines in Fig. 5. When the spreaders are not in use, they are held by spring-clasps 47 of any suitable character, and of course the spreaders need not both be pivoted to the same side of the frame.

When it is desired to fill the frame with leaves, the spring-roller is permitted to unwind sufficiently to reduce the tension of the tapes, and the frame is preferably arranged in the position shown in Fig. 2. The leaves can then be very easily arranged in proper position on the tapes, after which the spring-roller is wound up to the desired tension by means of the key. As the back is made of resilient material, it will of course be necessary to spread the edges thereof apart at some times for the purpose of removing or inserting leaves, and this is accomplished by means of the spreaders, which are arranged as shown in broken lines in Fig. 5 and forced into the position shown in Fig. 2 to spread the back and hold it in extended position. This enables the leaves to be freely inserted or removed, and when the spreaders are released the spring-roller is adjusted to clamp the back upon the leaves and draw the tapes taut and straight across the back from one edge to the other thereof. I have found that fiber board constitutes a very satisfactory material for the back, as it is inexpensive, light in weight, and can be readily formed into the desired shape and will to a more or less extent hold the shape to which it is set. I do not depend upon the resiliency of the back to clamp the leaves, but employ a spring-roller not only for the purpose of holding the tapes, but also to clamp the back upon the leaves.

The binder-frames will be made of different sizes; but it will be readily understood that each frame is capable of adjustment to hold a greater or less number of leaves—that is to say, a binder of the size indicated in the drawings, for example, can be reduced in size to

hold a comparatively few leaves by winding up the spring-roller sufficiently to clamp the edges of the back upon the leaves, or, on the other hand, the back can be extended by means of the spreaders to receive as many leaves as can be arranged on the tapes, and in both cases the binder will hold the leaves evenly and properly in place. Thus it will not be necessary always to use the spreaders in inserting or removing leaves, as at some times when a comparatively few leaves are in the binder it will be sufficient to simply lessen the tension of the tapes.

My improved binder is simple in construction, inexpensive to manufacture, and easy to operate. It is susceptible of various changes and modifications which I reserve the right to make; and it consists, essentially, of a single back capable of being extended or contracted and a single spring-roller to operate the tapes which connect the edges of the back and carry the leaves. When the binder is opened, the stub end of the leaves will spring up in the position shown in Fig. 1, and the leaves will lie flat, so that entries may be made thereon close to the bound edges. My improved leaf is especially adapted for use with binders of this kind, because the stub end of a book made with such leaves is capable of being compressed to less thickness than the major part of the book, and when the book is opened the stub end will spring up and the leaves will lie flat and close together at the bends therein without spreading and exposing the tapes, Fig. 1.

Without limiting myself to the exact construction and arrangement of parts herein shown and described, what I claim as new, and desire to secure by Letters Patent, is—

1. A binder-frame for loose-leaf books comprising a one-part round back made of resilient fiber board, and means carried by the back for holding the leaves and clamping the edges of the back thereon.

2. A binder-frame for loose-leaf books comprising a round back made of resilient fiber board and means connecting the edges of the back and holding the leaves, said means being flexible to permit the leaves to spring out away from the back when the book is opened.

3. A binder-frame comprising a round back made of resilient material, tapes connected with the edges of said back to receive and hold the sheets, and rotatable means for drawing the tapes taut and clamping the edges of the back upon the sheets.

4. A binder-frame comprising a back made in one piece of resilient material, tapes connected with the edges of said back to receive and hold the sheets, and a spring-roller for drawing the tapes taut and clamping the edges of the back upon the sheets.

5. A binder-frame comprising a back, a spring-roller located within said back at or about its center, and tapes fastened to said

spring-roller and passing across the back from one edge to the other for holding the leaves.

6. A binder - frame comprising a back, a spring-roller located within said back at or about its center, guides at one edge of the back, and tapes fastened at one end to said roller and passing over said guides and attached at the other end to the edge of the back for holding the leaves.

7. A binder-frame comprising a curved one-part back made of resilient material, covers

connected to the edges of said back, a spreader pivoted at or about its middle, one end of said spreader being pivoted at one edge of the back and the other end of the spreader being adapted to engage the other edge of the back, and a clasp on one of the covers to hold the spreader when not in use.
